UNITED STATES PATENT OFFICE.

TAYLOR G. BURKE AND MAUD BURKE, OF NEW YORK, N. Y.

INK-VENDING MACHINE.

Application filed July 18, 1925. Serial No. 44,428.

This invention relates to ink vending machines, and has for its object the provision of means whereby ink is supplied for filling fountain pens in return for a suitable coin. A further object includes the provision of a construction whereby ink is provided in quantities sufficient to fill a fountain pen in return for a deposited coin of proper value. Another object includes the provision of a coin operated mechanism for the purpose stated, which is comparatively simple in construction, efficient in operation and whereby ink in quantities sufficient to fill a fountain pen is exposed for a limited time. A still further object includes the provision of a timing mechanism whereby the ink is exposed for a sufficient period of time to fill a fountain pen.

Other objects will appear hereinafter, and I attain these objects by the construction illustrated in the accompanying drawings, in which

Fig. 1 is a sectional view in elevation of a construction which embodies the principles of our invention.

Fig. 2 is an end view thereof.

Fig. 3 is a view taken on the line 3—3 of Fig. 1, with the operating and timing mechanism omitted.

Fig. 4 is a plan view of the operating and timing mechanism taken on the line 4—4 of Fig. 3 looking in the direction of the arrows.

Fig. 5 is a view of the coin gripping device.

Like parts are designated by the same numerals throughout the several views.

It is among the prime purposes of our invention to provide an ink vending machine which is inexpensive to operate and which is well adapted to be stationed in public places for the convenience of persons who use fountain pens. To this end we provide, in a preferred construction, a casing 10 having a base 11 and a cover 12. At or near the bottom of the casing we provide an ink reservoir 13 to which is connected a pump 14 by a supply conduit 15 which may be provided with a suitable check valve (not shown) to prevent the ink from being forced back into the reservoir. Shaft 18 of the operating mechanism carries a rack 17 which operates a rack bar 19 on the piston 16 to thereby cause the pump to supply a limited quantity of ink to the gravity reservoir 20 through the conduit 21. From this reservoir, by

means of conduit 22, the ink is supplied to the pen filling well 23 in which operates a piston 24 to discharge the remaining ink into the drain basin 25 at the end of the time limit. From this basin the left over ink is returned to the return basin 26, when that is used, and from there to the reservoir 13 by a drain pipe 27. Obviously, this pipe may be attached directly to the drain basin 25 if desired, in which case basin 26 may be omitted. A cylinder drain 28 serves to carry off any leakage that may accumulate. Normally the piston 24 rests at the position shown in Fig. 1, as will be more fully stated below. In this position it is held by a cam member 29 acting on a bearing roller 30 which is connected on the piston stem 31 of piston 24. A spring 32 holds the cam roller in close engagement with the cam and thus insures positive operation to lower the piston to the position indicated in dotted lines, and thereby provide the ink filling well 23, in which the pen nib is dipped through the opening 33 in the casing. A guide 34 holds the roller 30 in proper position, and cam 29 is secured to shaft 18 in any suitable manner as by a nut 35.

The operating mechanism is so constructed as to be placed in operation in response to certain necessary acts including the insertion of a proper coin in the chute 36; and in the specific construction herein shown, winding the operative mechanism by giving the handle or key 37 a quarter turn. The shaft 38 on which the key 37 is connected terminates in a bearing 39 so as to be movable independently of the operating shaft 18. At a suitable position on shaft 38 there is fastened the coin engaging crank 40, the head 41 of which engages a deposited coin 42 as it rests on plate 43 to thus prevent the head 41 from ineffectively passing through the opening in the operating crank head 44 of the operating crank arm 45. Crank arm 45 is fastened to the operating shaft 18 which when a suitable coin has been inserted will be rocked as the key 37 is given a partial turn to thus wind the operating and timing mechanism in the manner described below. A spring 46 causes the return of the key.

The operating and timing mechanism may be of any suitable construction to quickly and inexpensively supply sufficient motive power to provide a limited supply of ink temporarily and for a long enough time to fill a single pen. This purpose we accomplish by the

operating and timing mechanism herein disclosed, and whereby the motive power operates the pump piston 16 to force ink into the gravity reservoir 20 and to again raise into normal position the temporarily lowered ink returning piston 24. The return of this piston is timed by the operating mechanism so as to permit the pen to be filled from the ink that is temporarily exposed in well 23.

10 The motive power herein is a power spring 50 which is wound up by giving the key 37 a quarter turn after a coin has been deposited. This turn will rotate the drive wheel 51 and wind spring 50 by means of a reduction gear 52. A retarding mechanism in the form of reduction gears 53, 54 and 55, and the butterfly fan 56 retards the return of the pistons to their normal position. It will be noted that the ratchet 57 permits the spring 20 50 to be wound up while the operating shaft 18 is given a turn. The extent of this turn is controlled by the stop limits 58 and 59 and the stop finger 60. At the same time pump piston 16 is caused to be depressed to thereby force ink into the gravity reservoir 20 in the manner stated above. At the same time, because of the rotation of shaft 18 and attached cam 29, the ink exposing piston 24 will be lowered to approximately the position 25 shown in the dotted lines in Fig. 1. When in this position a limited quantity of ink will fill well 23 above the lowered piston 24 to thus provide ink for filling a fountain pen. The pen is filled by opening the cover 33' 30 and dipping the pen nib into the ink well 23 through the opening 33 in the cover of the receptacle. While the pen is being filled the plunger 24 is caused to return to its normal position thereby preventing the filling of 35 several pens on the deposit of a single coin. The pump piston 16 is also returned at this time, to its upper or normal position in readiness for pumping a fresh supply of ink into the gravity reservoir 20.

40 45 When the supply of ink in the supply reservoir falls below a certain level the coin is automatically returned by means of the return chute 70. The mechanism for returning a coin includes an actuated trip release 71 which normally engages and holds the coin plate 43 in position. When, however, the float 72 is lowered, by reason of a low ink level, the finger 73 on the float stem 74 releases the trip 71. When this occurs, spring 50 55 75 will cause the plate to tilt to the position shown in dotted lines in Fig. 3. The coin is now free to pass through and out by way of the return chute.

Normally, the coin plate assumes the full 60 line position. The coin is then stopped by said plate and is engaged by the head 41 of the operating crank 40, to thus operate the ink pistons and to wind the spring for the purpose stated. When the pistons are 65 returned to their normal position, they shut off

the ink supply until another coin is inserted and the key is again turned as before.

An ink supply funnel 80 is provided for convenience in filling the reservoir. A cover 81 and padlock 82 are provided for closing 70 the funnel. A coin box 83 to receive the coins is provided, as they are released from the coin clutch mechanism which release is effected when the turning pressure of the key and operating mechanism is released. 75

Then the arm 40, by reason of its spring then quickly returns, this return action being faster than the timed return action of the operating crank arm 45, thus causing the coin to drop into the coin box. 80

The use of our vending machine is readily understood. If it is desired to fill a fountain pen of the "self-filling" type, a coin is dropped into the chute 36. The key is then given a turn until the stop is reached, which is about 85 a quarter of a turn. This action will lower both the ink cylinder plungers 16 and 24 in their respective cylinders, and piston 16 will force a limited supply of ink into the gravity reservoir 20 from which it flows into the pen 90 filling well 23 as soon as the conduit supply opening is uncovered. The pen may then be filled by inserting it through the opening 33 and into the well 23. While the pen is being filled piston 24 gradually returns to normal 95 and to close the well forces out any unused ink, which is returned, as explained above.

Having now described our invention, what we claim as new and useful, and desire to secure by Letters Patent is:

1. In an ink vending machine, the combination of means for detaching a predetermined quantity of ink from a source of supply, means for confining said quantity of ink in a limited space accessible for filling a fountain pen, timing mechanism for returning unused ink to its source of supply, and means for operating said mechanism. 105

2. In an ink vending machine, the combination of means for receiving a control device, including a crank, said crank rendered operative through the agency of said control device, and means for exposing a predetermined quantity of ink accessible for filling a fountain pen, and piston means for controlling said exposed ink. 110

3. In an ink vending machine, an ink reservoir having a conduit, a gravity ink feed connected to said reservoir by means of said conduit, means for supplying a predetermined quantity of ink to said gravity feed, means connected to said gravity feed for receiving and exposing a limited quantity of ink in a confined space for filling a fountain pen, and means for disposing of the ink 120 within a limited time. 125

4. In an ink vending machine, an ink reservoir having a conduit, a gravity ink feed connected to said reservoir by means of said conduit, a pump connected to said reservoir 130

for forcing a limited quantity of ink into said gravity feed, a well communicating with said gravity feed, and means for closing the communication between said well and said gravity feed.

5. In an ink vending machine, an ink reservoir having a conduit, a gravity ink feed connected to said reservoir by means of said conduit, a pump connected to said reservoir for forcing a limited quantity of ink into said gravity feed, a well communicating with said gravity feed, means for closing the communication between said well and said gravity feed to thereby obstruct the well, and
- 10 means for withdrawing said obstructing means, and means for rendering operative said obstruction withdrawing means.
- 15 6. In an ink vending machine, an ink well,

a storage reservoir having a piston for controlling the ink in said well, a gravity ink reservoir also having a piston for controlling the ink from said gravity reservoir, a cylinder for each of said pistons, common means for operating said pistons simultaneously to thereby cause ink from the storage reservoir 20 to be supplied to said gravity feed and ink from the gravity feed to be supplied to the cylinder in which the second piston operates, and means for rendering operative said pistons.

In testimony whereof we have hereunto set our hands on this 15th day of July, A. D. 1925.

MAUD BURKE.
TAYLOR G. BURKE.
